tion of Michigan

Original application August 15, 1935, Serial No.
36,247. Divided and this application June 25,
1936, Serial No. 87,214

7 Claims. (Cl. 200—116)

This invention relates to devices for making and breaking electric circuits and more particularly to electric circuit breakers automatically operable in response to current overload.

5 The object of the present invention is the provision of an improved and simplified adjustable mounting means for a current responsive bimetallic strip in an automatic electric circuit breaker.

10 Other objects and features of the invention will be readily apparent to those skilled in the art from the following specification and appended drawing illustrating certain preferred embodiments of the invention in which:

15 Figure 1 is a vertical sectional view of the circuit breaker according to the present invention.

Figure 2 is a view on reduced scale of the mechanism shown in the lower part of Figure 1
20 in a different position.

Figure 3 is a detail bottom view of the bimetal mounting.

Figure 4 is a detail front view of the bimetal mounting.

25 This application is a division of application, Serial No. 36,247, filed August 15, 1935, for Circuit breaker.

The circuit breaker illustrated in the drawing comprises an exterior enclosing box 1 having a movable cover 2. Within the enclosure is mounted a sealable multi-circuit circuit breaker comprised of an insulating base 3 and metallic cover 4 sealably secured to the base by means of rivets 5. The cover 4 is provided with a plurality of openings through which extend the operating handles 6. The enclosure cover 2 is provided with a generally central opening receiving a raised portion of the cover 4 and exposing the operating handles 6 to the exterior of the enclosure.

30 Within the circuit breaker is disposed a stationary contact plate 7 secured to the base by means of a stud 8. Cooperating with this contact plate are a plurality of floating contact bars 9 carrying contact surfaces 10 adjacent one 40 end. The contact bars 9 are provided with notches 11 received within the upper ends of slots 12 within one of the legs of members 13 which are guided by the base for rectilinear movement. Compression springs 14 bias the bars 9 for rotation about their pivotal engagement with the members 13. The operating handles 6 are generally L-shaped and have their interior legs provided with cam surfaces engaging the front of the members 13 to transmit

45 rotary movement of the handles into rectilinear movement of the members 13. Relatively weak compression springs 15 bias the handles 6 against the members 13 in the normal "on" position of the device to provide for overload tripped indication to be hereinafter described.

At the opposite ends of the base, connectors 16 are rigidly secured to the end flanges by spun-over portions of metallic inserts 17 and the interior ends of the connectors 16 have their central portions punched or pressed inwardly from 5 the main portion of the connector as at 18. To this portion of each connector is rigidly welded or otherwise secured one end of a bimetallic strip 19. The side arms 21 formed at the end of the connectors are bent over as at 22 and within 10 the spaces formed between the side arms 21, the bent over portions 22 and the central portions 18 are disposed blocks 23 through which are threaded studs 24 bearing against the free ends of the central portions 18 and serving as adjusting and calibrating means for the bimetallic strips 19. Flexible leads 25 interconnect the free ends of the bimetallic strips 19 and intermediate points on the contact bars 9. The metallic inserts 17 may be interiorly threaded for the reception of 20 terminal studs 26. The ends of the circuit breaker may be sealed off by means of fibre sheets 27 secured between the engagement of the cover 4 with the top of base 3.

The operation of the circuit breaker will now 25 be described.

The mechanism shown at the bottom of Figure 1 is in the normal operating position with the movable contact 10 pressed against the contact plate 7 by the compression spring 14 and the contact bar 9 latching engaged at its opposite end by the bimetallic strip 19. To move the parts to manual "off" position the handle is rotated about its engagement with the metallic cover 4 into the position shown in reverse at the 30 top of Figure 1, whereupon the cam surface formed by the interior leg of the handle moves the member 13 toward the bottom of the base 3, thus forcing the contact carrying end of the bar 9 out of engagement with the plate 7 and 35 interrupting the current through the mechanism. To again place the parts in closed circuit position the handle is rotated in the opposite direction.

When an overload occurs through any breaker mechanism while in the normal closed circuit position shown at the bottom of Figure 1, the bimetallic strip 19 will flex or bend downwardly until it releases the contact bar 9 which will then rotate about its engagement with the member 13 under the bias of the compression spring 14, thus moving the parts into the position shown in Figure 2. As the spring 15 is relatively weak compared with spring 14, the release of the contact bar by the bimetallic strip results in the corresponding handle 6 being moved outwardly into its indicating position as shown in Figure 2. To reset the breaker mechanism after automatic trip, the handle is operated as a push button and upon pushing inwardly the member 13 will be moved 50 55 60

toward the bottom of the base whereupon the contact bar 9 will be rotated about its engagement with the member 13 until its latching end again moves in back of the latching end of the bimetallic strip 19, whereupon if the bimetallic strip has in the meantime cooled sufficiently to resume its normal position, release of the handle will permit the parts to assume the position shown at the bottom of Figure 1.

10 The bimetal mounting herein disclosed constitutes a very simple and economical means for supporting and adjusting the circuit breaker. This mechanism involves a minimum of parts which can be readily assembled and it is seen that movement of the stud 24 will cause bending of the central pressed out portion 18 of the connector to move the free end of the bimetallic strip 19 so as to cause more or less overlapping of the contact bar 9 and hence to determine the 15 value of current which will cause the corresponding breaker mechanism to operate within a given length of time.

While the invention herein claimed has been disclosed in connection with the multi-circuit 25 type of circuit breaker claimed in the parent application, it is obvious that it is equally as well adapted to single and multipole types of circuit breakers and to circuit breakers using distinctive mechanisms, and while certain preferred embodiments of the invention have been specifically disclosed, it is understood that the invention is not limited thereto as many variations will be readily apparent to those skilled in the art and the invention is to be given its broadest possible interpretation within the terms of the following 30 claims.

What is claimed is:

1. In an automatic electric circuit breaker, 40 relatively movable contacts, means for automatically moving said contacts to separated position including a current responsive bimetallic strip, a sealable enclosure for said contacts and means, an electrical connector rigidly mounted at the exterior of said enclosure and forming a circuit 45 terminal, said connector extending into said enclosure, one end of said bimetallic strip being rigidly secured to the connector adjacent to the interior end thereof, means electrically connecting the free end of the bimetallic strip to one 50 of said relatively movable contacts, and means for controllably moving the interior end of said connector to provide adjusting means for the circuit breaker.

2. In an automatic electric circuit breaker 55 having relatively movable contacts, manual means for effecting relative movement of said contacts to engaged and separated positions and automatic means for effecting relative movement of said contacts to separated position and including a current responsive bimetallic element, a sealable enclosure for said contacts, manual means and automatic means, a portion of said manual means extending through said enclosure to form an exterior operating handle, an electrical connector of generally L-shape, the base of the L being rigidly mounted at the exterior of the enclosure and forming a circuit terminal, the leg of the L being relatively free and extending into the interior of the enclosure, one end of the bimetallic element being rigidly secured adjacent 65 to the free end of said leg, means electrically connecting the free end of said element to one

of said contacts, and means for controllably moving at least a portion of said leg to provide adjusting means for the breaker.

3. In an automatic electric circuit breaker, 5 relatively movable contacts, means for automatically moving said contacts to separated position including a current responsive bimetallic element, a connector rigidly supported at the exterior of the circuit breaker and having its interior end relatively free, a portion of said free end being movable relatively to the remaining portion of said free end, one end of said element being rigidly secured to said first portion, and means for controllably moving said first portion to adjust the circuit breaker. 10

4. In an automatic electric circuit breaker, 15 relatively movable contacts, means for automatically moving said contacts to separated position including a current responsive bimetallic strip, a connector leading to the exterior of the circuit breaker, the interior end of the connector having a center strip cut from the side portions and movable relative thereto, one end of said bimetallic strip being rigidly secured to said center strip, means bridging said side portions, and a stud 20 threaded in said bridging means and bearing against the center strip to provide adjusting means for the breaker. 25

5. In an automatic electric circuit breaker, 30 relatively movable contacts biased to separated position, a current responsive bimetallic strip restraining such movement of said contacts, a rigid connector leading to the exterior of the circuit breaker, the interior end of said connector having a center strip bent from its normal plane, 35 one end of said bimetallic strip being rigidly secured to the end of said center strip, means bridging the side pieces in the normal plane of the connector, and a stud threaded in said bridging means and bearing against said center strip 40 to provide adjusting means for the breaker. 45

6. In an automatic electric circuit breaker, 50 relatively movable contacts biased to separated position, a current responsive bimetallic strip restraining such movement of said contacts, a rigid connector leading to the exterior of the circuit breaker, the interior end of said connector having a center strip bent from its normal plane, one end of said bimetallic strip being rigidly secured to the end of said center strip, a block 55 having a tapped hole disposed between the main body of said connector and said center strip, a stud in said hole bearing against said center strip to provide adjusting means for the breaker, and means electrically connecting the free end of said bimetallic strip to one of said relatively movable contacts. 60

7. In an automatic electric circuit breaker, 65 relatively movable contacts, biased to separated position, a current responsive bimetallic strip restraining such movement of said contacts, a rigid connector leading to the exterior of the circuit breaker, the interior end of said connector having a center strip bent from its normal plane, the remaining side pieces having their ends bent 70 over to provide retaining flanges, a block disposed and supported between said center strip, side pieces and flanges, and a stud threaded in said block and bearing against said center strip to provide adjusting means for the breaker. 75

JOHN G. JACKSON.
